CLAIM

The ornamental design for a foot conforming member for use in a shoe, as shown and described.

DESCRIPTION

FIG. 1 is a top view of an embodiment of a foot conforming member for use in a shoe according to the invention;

FIG. 2 is a bottom view thereof;

FIG. 3 is a side view thereof;

FIG. 4 is a view from the other side thereof;

FIG. 5 is a front view thereof;

FIG. 6 is a rear view thereof;

FIG. 7 is a perspective view thereof; and,

FIG. 8 is a view of the invention in a shoe.

The broken line showing of the shoe in FIG. 8 is for illustrative purposes only and forms no part of the claimed design.
